MACHINE FOR CONDITIONING LIQUIDS
WITH GASESRoger Dering, Salt Lake City, Utah, assignor to
Combined Metals Reduction Company, Salt
Lake City, Utah, a corporation of Utah

Application April 26, 1949, Serial No. 89,632

12 Claims.

1

This invention relates to so-called conditioners, as employed industrially for intimately intermixing gases with liquids for various purposes.

Machines of this type are used extensively in the metallurgical art for conditioning metallurgical pulp with reagents in order to accomplish various chemical or physical reactions on the pulp to further the recovery of mineral values therefrom.

Principal objects of the invention are:

To provide a conditioner unit which will effect an especially intimate intermixture of a gas with a liquid.

To provide such a machine which is particularly useful in the metallurgical field.

A feature of the present invention resides in the provision of an agitation chamber which is separate from the aeration or gas-injection chamber of the machine, and in the provision for dynamic passage of aerated or gasified liquid from the aeration chamber into the agitation chamber by way of an agitating impeller.

Further objects and features of the invention will be apparent from the following detailed description of the presently preferred embodiment thereof illustrated in the accompanying drawing by way of example and not of limitation.

While a conditioner of the type herein specifically disclosed is commonly employed to condition metallurgical pulp in advance of treatment by flotation, the broad concepts of the present invention are applicable to flotation machines as such. The application of such concepts specifically to flotation machines is disclosed in a separately filed patent application.

In the drawing:

Fig. 1 represents a side elevation of the machine, the view being partly in vertical section taken on the line 1—1 of Fig. 2;

Fig. 2, a horizontal section taken on the line 2—2 of Fig. 1;

Fig. 3, an enlarged detail of the aeration or gas-injecting impeller as illustrated in Fig. 1;

Fig. 4, a cross-section taken on the line 4—4 of Fig. 3; and

Fig. 5, an enlarged detail view of the agitation impeller, the view showing a cross-section taken on the line 5—5 of Fig. 1 and being drawn to a somewhat smaller scale than the views of Figs. 3 and 4.

Referring to the drawing: the illustrated embodiment of the invention comprises a cylindrical container or tank 9, within which is positioned, in spaced relation thereto and preferably by means of vertically extending spacer plates

(Cl. 261—93)

2

10, a smaller cylindrical container or tank 11. Between the containers 9 and 11 is defined a cup-shaped aeration or gas-injection chamber 12, and within the container 11 is defined an agitation chamber 13.

10 A conduit 14 leads into the chamber 12 from a source of liquid to be conditioned, entering the chamber at an upper level thereof, while a conduit 15 leads from the agitation chamber 13 at the level of the conduit 14. Such conduit 15 serves to conduct fully conditioned liquid to a point of utilization, further treatment, or storage.

The bottom of the container 11 is preferably provided by a cheek plate tray 16, which is supported in position by an inwardly-extending flange 11a and which defines a central opening into which fits a depending, annular lip 17a of an agitation impeller 17.

The agitation impeller 17 provides passage for aerated or gas-conditioned liquid from chamber 12 to agitation chamber 13, and serves to effect a dynamic passage thereof from the one chamber to the other. In the present instance, the agitation impeller 17 is constructed in the form of a hollow disk divided into a plurality of radial liquid-ejection passages 18, Fig. 5, by means of a series of radial partitions 17b. The passages 18 communicate at their inner ends with an intake orifice 19 defined by the depending annular lip 17a, and form a corresponding plurality of outlets 18a about the circumferential rim of the disk. Accordingly, such agitation impeller is operative to dynamically pass liquid from chamber 12 to chamber 13.

35 The impeller 17 is fixed for rotation on a tubular shaft 20, which passes axially through the center of the impeller and of its intake orifice 19 and terminates within the chamber 12 in spaced relation to the bottom of container 9.

40 Fixed to the lower end of the tubular shaft 20 is a disk-type aeration or gas-injection impeller 21. Such impeller 21 is preferably of a novel construction, affording superior dissemination of air or other gas in the liquid to be conditioned. As illustrated, the impeller 21 has a receiving recess 22 centrally located in its upper surface, into which is tightly fitted the lower end of the tubular shaft 20. The recess 22 is countersunk to provide a chamber 23, from which lead 45 a plurality of radial air or other gas ejector passages 24 desirably of tubular formation as shown. The circumferential periphery of impeller 21 is retrocedent, that is to say symmetrically notched, to provide ports of entry 25 for the air or other 50 gas as it discharges from the respective ejector 55

passages 24, it being understood that such passages open into the respective ports of entry. For obtaining an especially effective mixture of air or other gas with liquid contained by the chamber 12, such ports of entry 25 are formed with a radial leading portion 25a and a concavely arcuate trailing portion 25b.

In instances where reagents, usually liquids, are to be added to and intermixed with the liquid to be conditioned, for example in the conditioning of a metallurgical pulp prior to flotation, a tube 26 of smaller diameter than the tubular shaft 20 is inserted longitudinally and concentrically within such shaft 20 so as to terminate within impeller 21 preferably just above chamber 23 thereof.

The tubular shaft 20 is mounted for rotation within an elongate bearing assembly 27, making up part of a supporting superstructure 28 which rests upon the container or tank 9 as by means of cross-beams 29. Rotation of such shaft 20 may be effected by any suitable means, for example by an electric motor (not shown) belted to a drive pulley 30 which is rigidly fixed to the shaft.

The air or other gas is delivered to chamber 23 of impeller 21 through the tubular shaft 20, in the present instance through the annular longitudinal passage 31 defined between the reagent delivery tube 26 and the walls of such shaft 20. For introducing air or other gas into passage 31, a pipe-fitting 32 is mounted at the upper end of tubular shaft 20 by means of a conventional rotary joint assembly 33. A pipe 34 supplies air or other gas to pipe-fitting 32, and thus to shaft 20, from any suitable source of same. Preferably, the source is a pressure source, such as an air compressor or a pressure tank of gas, so there will be a forcible introduction of air or other gas into the centrifugal impeller 21.

In operation, air or other gas is forcibly discharged, together with a reagent, into the body of liquid to be conditioned within chamber 12 by means of the impeller 21. A continuous stream of the liquid to be conditioned enters chamber 12 through the supply conduit 14, passes downwardly into the zone of activity of impeller 21, and is sucked upwardly by means of the agitation impeller 17, passing through such impeller into agitation chamber 13.

The agitation impeller 17, thus, acts not only to agitate the body of liquid within chamber 13, but also acts in a measure as a pump, dynamically assisting the liquid to pass upwardly through the passage 19. Such impeller also acts to fling the aerated or gas-containing liquid from chamber 12 outwardly into the agitated liquid of chamber 13, thereby increasing dissemination of the air, or other gas, and the reagent throughout the liquid.

The fully conditioned liquid which rises to the surface of agitation chamber 13 is taken off through conduit 15, while more or less recirculation of the conditioned liquid between chambers 12 and 13 is provided for by a vertically-disposed series of openings 35 formed in the wall of the inner container or tank 11 remote from the liquid-supply conduit 14 and below liquid-outflow conduit 15. Removable and replaceable plugs 36 provide for closing off whichever of the recirculation openings 35 are not required in any given instance.

It should be noted that the spacer plates 10 function as baffles for short-circuiting flow of the

incoming liquid from supply conduit 14, in the one instance, and recirculation flow from openings 35 in the other instance. For this purpose, such baffles advantageously extend throughout the full length of the inner container or tank 11, and are advantageously located, circumferentially of container or tank 9, midway between conduit 14 and openings 35, as shown.

Since both of the impellers 17 and 21 are fixed to the tubular shaft 20, in spaced relationship at the lower end thereof, both rotate simultaneously. Furthermore, impeller 21 serves, in addition to its primary purpose, as a booster for impeller 17.

Whereas this invention is here illustrated and described with respect to a particular and a presently preferred embodiment thereof, it should be understood that various changes may be made therein and various other forms of the invention may be constructed on the basis of the teachings hereof, by those skilled in the art, without departing from the protective scope of the following claims.

I claim:

1. A machine for conditioning liquids with gases, comprising a gas-injection tank; means for supplying a liquid to said tank; means for injecting a gas into the liquid within said tank; an agitation tank disposed within said gas-injection tank and spaced upwardly from the bottom thereof, said agitation tank having a closed bottom and side walls which completely separate the interiors of said tanks; passage means leading through said closed bottom from the said gas-injection tank to the said agitation tank; an agitation impeller operatively disposed within said agitation tank above said passage means and adjacent the said bottom so as to be completely submerged and surrounded by liquid without access to the atmosphere, for aiding elevation of liquid therethrough and for agitating the liquid within said agitation tank; and outflow means leading from said agitation tank.

2. The combination recited in claim 1, wherein the gas-injecting means is an impeller provided with gas-injector passages; and wherein the agitation impeller is mounted above said gas-injecting impeller on a drive shaft which is common to both.

3. The combination recited in claim 2, wherein the agitation tank is spaced apart from the walls of the gas-injection tank; and wherein passage means are provided through the agitation tank at the upper part thereof affording recirculation flow between said tanks.

4. The combination recited in claim 3, wherein a pair of baffles are disposed between the two tanks at opposite sides thereof, for short circuiting and segregating liquid supply and liquid recirculation.

5. The combination recited in claim 4, wherein the two tanks are cylindrical and concentric.

6. The combination recited in claim 5, wherein the two impellers are mounted in common on a single drive shaft which is a tube through which gas is supplied to the gas-injecting impeller; and wherein a connection is provided adjacent the upper end of said tube for a source of gas under pressure.

7. The combination recited in claim 6, wherein the gas-injecting impeller comprises a disk having a retrocedent rim providing a plurality of enlarged ports of entry inwardly of the circumferential periphery of the disk for the gas as it is discharged into the liquid to be conditioned;

and gas-ejecting passages extending from intake communication with the drive shaft tube to outlet communication with the respective ports of entry.

8. The combination recited in claim 7, wherein a gas-injecting impeller is provided with a central chamber from which the gas-ejecting passages lead; and wherein a second tube is provided within and concentric with the drive shaft, said tube leading into said chamber for the purpose of supplying a reagent to the gas-injecting impeller.

9. A machine for conditioning liquids with gases, comprising a gas-injection tank; an agitation tank within but spaced apart from said gas-injection tank said agitation tank having a closed bottom and side walls which completely separate its interior from the interior of said gas-injection tank; an opening in said closed bottom of the agitation tank establishing communication between the two tanks; an agitation impeller disposed above said opening and adjacent said bottom of the agitation tank so as to be completely submerged and surrounded by liquid within said tank without access to the atmosphere; and a gas-injection impeller disposed below said opening.

10. The combination recited in claim 9, wherein recirculation passage means is provided between said tanks.

11. The combination recited in claim 10, wherein short-circuiting baffles are provided between said tanks at opposite sides of the recirculation passage means.

12. A machine for conditioning liquids with gases, comprising a cylindrical gas-injection tank; a concentric agitation tank within but spaced apart from said gas-injection tank; an opening centrally disposed in the bottom of said agitation tank establishing communication between the two tanks; a tubular drive shaft extending along the longitudinal central axes of said tanks and through the said opening; an agitation impeller fixed to said shaft above said opening, and having an annular lip depending into and rotatably fitted within said opening, said lip defining the intake mouth of said impeller; and a gas-injecting impeller fixed to said shaft below said opening, said impeller being provided with gas-ejector passages which are in communication with the hollow interior of said drive shaft.
